UNITED STATES PATENT OFFICE.

ALFRED S. ORCHARD, OF PHILADELPHIA, PENNSYLVANIA, ASSIGNOR TO THOMAS J. CARTER, OF INDIANAPOLIS, INDIANA.

DESIGN FOR A FONT OF PRINTING-TYPE.

SPECIFICATION forming part of Design No. 37,357, dated February 28, 1905.

Application filed July 26, 1904. Serial No. 218,299. Term of patent 7 years.

To all whom it may concern:

Be it known that I, ALFRED S. ORCHARD, a citizen of the United States, residing at Philadelphia, in the county of Philadelphia and State of Pennsylvania, have invented a new, original, and ornamental Design for a Font of Printing-Type, of which the following is a specification.

Said original design for a font of type is clearly illustrated in the accompanying drawing, wherein the distinguishing characteristics thereof may be readily seen, said drawing being a typographical impression of a font of type of said design.

What I claim as new, and desire to secure by Letters Patent, is—

The ornamental design for a font of printing-type as shown in the accompanying drawing.
